APPARATUS FOR THE METAL SPRAY
COATING OF TUBESIsrael H. Marantz, New York, N. Y., assignor to
Columbia Cable & Electric Corporation, Brook-
lyn, N. Y., a corporation of New York

Application April 9, 1949, Serial No. 86,532

2 Claims. (Cl. 118—320)

1 Unless metal tubes of the type used in electrical installations, as they come from the forming mill, are first cleaned by removing the adherent lubricating grease and oils, rust and grit from the outer and bore surfaces of the tube, and unless the tubes are dried before coating with the required corrosion resistant metal or paint, such coatings may not adhere adequately and unless the cleaning and coating processes and drying of the paint coating can be performed at a relatively high rate of speed without manual labor or waste of material, the cost of manufacture of the finished product may be excessive and not justified by the price at which such tubes may be sold.

Where high temperature for long periods is resorted to for application of the metal outer coating, the outer surface of the tube may harden unduly and tend to crack or split, upon the bending frequently required in installation. A 20 non-ferrous metal coating alloyed with the tube, such as an iron zinc alloy coating is less ductile and pliable than the tube itself and thus tends to crack or peel off especially in bending.

Where the metal coated surface of the tube is relatively smooth, it slips too readily in the hand and affords insufficient friction for application of the field bending tool, and does not readily afford a tight electric connection and so has a tendency to open too readily under vibration; moreover an outer coating of paint or the like will have inadequate adhesion upon such smooth metal coating and will readily crack or peel off such smooth tube, especially when bent.

While a pure non-ferrous metal coating may be applied by electroplating, the equipment and installation and the maintenance and power costs are high while the operation is relatively slow and results in the objections above pointed out to a smooth coating.

It is a fundamental object of the invention to provide a substantially fully automatic, continuous, installation, expeditiously and reliably to convert the smooth steel tube as originally formed with lubricating grease, oil and grit adhering thereto and which is likely to become rusty, into a finished, interiorly and exteriorly degreased and cleaned and exteriorly roughened and metal sprayed and interiorly painted tube.

More specifically it is an object to provide an installation of low maintenance cost, automatically to remove the grease, oil, rust and grit from the metal tubes, to roughen the outer surface thereof, to clean out the bore of the metal tube

5 and uniformly to metal spray the exterior of such tube and then to paint the interior of such tube and dry such paint, which installation is capable of continuous operation at relatively high speed for long periods with a minimum of supervision, and the working parts of which are readily accessible for maintenance and repair.

Another object is to provide an installation for metal coating the outer surface of metal tubes 10 without the use of high temperature for long periods of time and with consequent avoidance of the objections above pointed out to the surface hardening of the tube under heat; which coat is not of alloy character and avoids the objections of peeling or cracking off especially when the tube is bent and which coating is not so smooth that a coat of paint or of another metal thereon will tend to peel or crack off therefrom especially in bending the tube.

Another object is to provide a mechanism that 15 may readily be incorporated in a continuously moving conveyor system, successively to remove such tubes from the conveyor, clean the bores of the tubes and thereupon restore the tubes to said conveyor to be advanced thereby.

Another object is to provide a metal tube having a non-ferrous metal coating on the entire outer roughened surface thereof having a mat finish, which coating is of ductility and pliability 20 no less than that of the metal tube covered thereby so that the tube may be bent without cracking or peeling off of the coating thereon.

In practicing the invention desirably, the following sequence is effected; lengths of metal 25 tubes are passed through a degreasing unit and discharged in spaced relation upon a conveyor system which simultaneously rotates the tubes while advancing them lengthwise through a roughening unit which cleans off carbon and rust 30 deposits and roughens the outer surface of such tubes. The roughened tubes are thereupon advanced in sequence by said conveyor system to a blowout unit which removes the tubes from the conveyor system to present such removed tubes to an air nozzle which discharges a jet of air therethrough and thereupon replaces such tubes upon the conveyor system to be advanced thereby to the metal spraying unit. For the metal spraying operation, means are provided positively to 35 grip the tubes and simultaneously rotate and advance the tubes at a controllable, relatively high rate of speed past metal spray guns which therefore deposit a uniform non-ferrous metal coating thereupon of any desired thickness. The sprayed 40 tubes are thereupon conveyed to a painting unit

55

and desirably presented thereto at an incline, which painting unit injects a quantity of paint into the bores of the tubes, the latter thereupon being rotated to distribute such paint upon the entire inner surface thereof. If desired, burnishing means may be provided between the spraying operation and painting operation to smooth slightly the roughened outer surface of the tube.

The finished article formed by such installation has a roughened outer surface with congealed non-ferrous metal particles thereon and completely covering such outer surface with a mat finish, the metal coating being of ductility and pliability no less than that of the metal tube covered thereby, so that the latter may be bent without cracking or peeling off of the coating thereon.

In the accompanying drawings in which are shown one or more of various possible embodiments of the several features of the invention,

Fig. 1 is a diagrammatic view of the system, with parts broken away,

Fig. 2 is a diagrammatic cross sectional view taken along line 2—2 of Fig. 1,

Fig. 3 is a diagrammatic perspective view of the blow-out unit,

Fig. 4 is a view similar to Fig. 2 taken along line 4—4 of Fig. 3,

Fig. 5 is a longitudinal cross sectional view taken along line 5—5 of Fig. 1,

Fig. 6 is a view similar to Fig. 2 taken along line 6—6 of Fig. 5,

Fig. 7 is a view similar to Fig. 2 taken along line 7—7 of Fig. 1 and,

Fig. 8 is a view similar to Fig. 2 taken along line 8—8 of Fig. 1.

Referring now to the drawings in which is illustratively shown one embodiment of the invention, as diagrammatically shown in Fig. 1, the installation desirably comprises a plurality of operating stations which successively act upon the tubes to form the completed product.

These operating stations may include a vapor degreasing station A for removing lubricating grease or oils from the surface of the tube, a roughening station B for roughening and cleaning the outer surface of the tube, a blow-out station C for removing grit or dirt from the bore of the tube, a metal spraying station D for applying a metal coating to the exterior of the tube and a painting station E for coating the interior of the tube, suitable mechanism being provided at each of said stations to perform the required operation.

In order successively to advance the tubes from station A to station D, a conveyor F is provided which may include a sequence of continuously rotating skew rollers, or, if desired, a positive feed mechanism G. However such positive feed mechanism G is preferred to advance the tubes through the metal spraying station to the painting station E. Suitable conveyor means H remove the tubes from the painting station and act upon such tubes in order equally to distribute and dry the paint on the inner surface thereof.

If desired, burnishing station I having positive feed mechanism G¹ associated therewith and, if desired, positive feed mechanism G², may be interposed between the outlet of the metal spraying station D and the internal painting station to act upon the outer surface of the tubes and reduce the roughness thereof, and transfer means J may be provided to receive the tube from posi-

tive feed mechanism G² to present it to the painting station E.

Having thus described the general outline of the machine, the specific component elements thereof will now be described in detail.

Vapor degreasing station "A"

Here the grease or oil and incidentally much of the grit is, in part, automatically removed and in part converted into carbon black still adherent to the tubes. Though the degreasing instrumentality may be of any of numerous possible types, a particularly desirable arrangement is that diagrammatically shown in Figs. 1 and 2.

A tall rectangular degreasing tank 11 has preferably a partition 12 across its width, illustratively of approximately one-third the height of the tank, dividing it into two substantially identical compartments 13 and 14 charged with a suitable liquid grease removing solvent such as trichloroethylene. Vertical conveyors 15 and 16 are disposed at opposite sides of partition 12 and each extend substantially the height and width of tank 11.

As shown in Figs. 1 and 2 each vertical conveyor 15 and 16 may comprise two pairs of vertically aligned continuously driven rollers 19 and 21, one pair of rollers at each side of the tank, respectively near the bottom and top thereof. Each pair of vertically aligned rollers is connected by an endless belt 22 which has a plurality of equally spaced carrying fingers 23, extending from the outer face thereof at substantially right angles thereto. Although the fingers 23 of each pair of endless belts 22 of each of said conveyors 15 and 16 could be transversely aligned, those on one belt are desirably in advance of those on the other as shown in Fig. 1, so that when a metal tube 24 is positioned on each associated pair of fingers on the two belts of the conveyor 15 in the manner hereinafter described, the metal tube 24 will be supported at a slight inclination as shown.

To feed such metal tubes 24 onto conveyor 15 as from a source of supply (not shown), an inclined table 25 may be provided rigid with and extending transversely across the upper edge 26 of the wall 27 of the tank 11. In order to release the metal tubes 24 one at a time from table 25 so that they may successively be discharged onto successive pairs of associated fingers 23 of conveyor 15, upstanding stop means 28 are provided adjacent the lower portion 29 of inclined table 25. Such stop means may comprise a ledge extending transversely across the face of table 25. Means are desirably provided associated with said stop 28 to lift the lowermost metal tube 24¹ on the inclined table 25 over stop 28 so that it may slide onto fingers 23. Such means may comprise a pair of normally retracted plungers 31 on each side of table 25 respectively and transversely aligned thereacross. Each plunger may have an inclined upper face 32 adapted to extend through an opening 33 in said table 25 beneath the lowermost metal tube 24¹ that is restrained by stop 28. Actuating means 34 of any suitable type are associated with each of the plungers 31 to raise and lower the latter, whereby when the plunger 31 is raised it will lift said lowermost tube 24¹ which will slide off the inclined face 32 over stop 28 onto the associated pair of carrying fingers 23 of conveyor 15.

As the conveyors 15 and 16 are both driven in a counterclockwise direction, as shown in Fig. 2, conveyor 15 will first carry the tubes 24 on suc-

cessive pairs of associated fingers 23 in a downward direction.

In order to provide for continuous advance of the tubes, even when they reach the bottom of the tank 11 in which position the carrying fingers 23 will extend vertically downward, a curved plate 36 may be affixed across the bottom of the tank, concentrically with the bottom rollers 21 of each of the conveyors 15 and 16 and spaced therefrom by little more than the length of fingers 23 as shown. Thus, as the direction of travel of the endless belts 22 changes from a downward direction to an upward direction, as the fingers 23² for instance, reach vertically downward position, the tube 24³ carried thereby will slide downwardly therefrom against the curved plate 36, and will then be picked up by the next pair of fingers 23³.

Thus the tubes are successively immersed in and lifted out of the degreasing bath in compartment 13.

As the tubes on conveyor 15 are advanced in an upward direction and start to emerge from the compartment 13, they will be successively transferred to conveyor 16. For such transfer a pusher device is employed which may comprise a pair of transversely aligned arms 38, one on each side of the tank, pivoted at their upper ends as at 39 and weighted at their free ends as at 41. Thus as the topmost tube 24³ on conveyor 15 abuts against arms 38, it will be pushed thereby outwardly on the associated carrying fingers 23 against partition 12, the upward movement of the fingers 23 at the same time pivoting arms 38. As the movement of the conveyor 15 finally raises the tube 24³ above the upper edge 42 of the partition 12 the weighted pivoted arms 38 will be free to move toward partition 12 thereby pushing tube 24³ over said upper edge onto an associated pair of fingers 23 on conveyor 16. At the same time the arms 38 will abut against the next succeeding tube 24⁴ on conveyor 15 for the next transfer operation. Conveyor 16 will carry the tubes thereon through the relatively clean degreasing bath in compartment 14, and then through the vapor zone 37 above compartment 14 until the uppermost tube 24⁵ on conveyor 16 abuts against the pivoted arms 43 of a second pusher device. As the construction and operation of the arms 43 is identical to that of the arms 38, they need not be further described and will function in similar manner to discharge successive degreased tubes onto a downwardly inclined chute or guide 44 which directs the tubes onto conveyor system F.

As the metal tubes have desirably been retained at a slight inclination as they pass through the degreasing tank 11, the solvent therein may readily drain from the bore of such tubes as they successively are lifted out of the bath in compartment 14 and through the vapor zone 37, and because of the heat of the bath and the vapor zone, the tubes will be heated sufficiently to dry the same.

Although the chute or guide 44 could be of any one of a number of constructions, including conveyor belts similar to those of conveyors 15 and 16, it illustratively comprises a downwardly inclined table or plate 45, the upper edge 46 of which is affixed to the upper edge of wall 40 of the tank 11 and extends transversely thereacross. Desirably associated with each of the lateral edges of table 45 are inwardly extending flanges 47 extending parallel to and spaced from table 45 which flanges retain the tubes on table 45 as

they slide down the latter. To conserve space, a second inclined table 48 is desirably provided at the end of flanges 47 extending at right angles thereto toward wall 40. Table 48 also desirably has associated therewith at each of the lateral edges thereof inwardly extending flanges 49 extending parallel to and spaced from table 48.

In order to prevent the inclined metal tubes from jamming in the chute 44 as they slide down the latter, means are desirably provided to position such tubes so that they will be at right angles to their path of movement down the chute. Such means may comprise a pair of retractable plungers 50 positioned respectively on table 45 near the upper edge thereof and transversely aligned thereacross, each of said plungers 50 normally projecting through an opening 50' in such table 45. Thus when a metal tube 24⁶ is discharged at an inclination from conveyor 16 it will slide against projecting plungers 50 and hence be positioned at right angles to its path of movement down the chute. In order to release the tube retained against such plungers 50, actuating means 51 are provided, illustratively similar to actuating means 34 previously described, and positioned beneath table 45 to retract such plungers 50.

As diagrammatically shown in Fig. 2 the lower edge of table 48 has an upstanding stop 53 which may comprise a ledge extending transversely across such lower edge and against which the lowermost tube 24⁷ in the chute will abut. Means are desirably provided associated with said stop 53 to lift the lowermost metal tube 24⁷ on table 48, over stop 53 so that one tube at a time may be ejected from the chute onto conveyor F. Such means may comprise a pair of normally retracted plungers 54 on each side of table 48 respectively, and transversely aligned thereacross. Each plunger may have an inclined top face 55 adapted to extend through a corresponding opening 56 in table 48 beneath tube 24⁷. Actuating means 57, which may be similar to actuating means 34 previously described, are associated with the plungers to raise and lower the latter, whereby when plungers 54 are raised they will lift such lowermost tube 24⁷ which will slide off the inclined face 55 of the plunger, over stop 53, onto the conveyor F.

The tubes thus passed through the degreaser in direction at right angles to their length are desirably next propelled lengthwise in sequence for the roughening operation which follows degreasing.

For this purpose, as illustratively shown in Figs. 1 and 2, the plurality of skew rollers 61 of conveyor system F desirably lie in the same plane extending along a line parallel to the lower edge 62 of table 48, parallel to each other and at an angle to such line. The skew rollers 61 function in conventional manner, that is, when they are rotated in a clockwise direction as shown in Fig. 3, they will simultaneously rotate and advance the metal tubes thereon.

In order that tubes 24 may be fed one at a time to the skew roller conveyor system F and be slightly spaced lengthwise thereon, the speed of rotation of conveyors 15 and 16 and of conveyor system F, and the operation of actuating means 34, 51 and 57 must be properly correlated and it is therefore essential that they operate in proper timed relation with the movement of such conveyors. To this end a timer 63 is desirably provided, which is illustratively shown positioned

above tank 11 and having a trip arm 64 actuated as by the fingers 23 of conveyor 15 as they are successively advanced. The timer is connected by suitable means (not shown) to the actuating means 34, 51 and 57 so that they will respectively feed a tube into the degreasing machine, release a tube down the chute and eject a tube onto conveyor system F in properly timed sequence.

Roughening station "B"

In order to clean the outer surface of the metal tubes, that is to remove residues of degreaser and carbon deposit therefrom as it is advanced by the skew roller conveyor system F, and also to roughen said surface, the tubes are passed through a roughening station E. Although any suitable means may be used to roughen the outer surface of the tubes such as chemical or mechanical means, illustratively mechanical means are used including a blasting unit 71 which unit may be conventional in construction and so need be described but very briefly.

As the tubes are simultaneously rotated and advanced by conveyor system F, abrasive material is hurled thereagainst by the centrifugal rotor 72 thereabove supplied from hopper 73, thereby to insure effective cleaning and uniform roughening of the entire outer surface of each tube. A housing 74 encompassing that portion of the skew roller conveyor system F below rotor 72 collects the abrasive material and the particles removed thereby from the tubes, from which housing the abrasive may be returned to hopper 73 by means of a suction system 75.

It is of course to be understood that other mechanical blasting means could be used such as a jet designed to hurl abrasive particles against the tubes. Although one jet could be used a plurality are preferred to insure roughening of the entire surface of the tubes.

Tube bore blow-out station "C"

Since abrasive particles are likely to collect in the interior of the tube during its traverse through the roughening station, these are now removed by causing the skew roller conveyor system F to convey the tubes successively past the blow-out station C.

As diagrammatically and illustratively shown in Figs. 3 and 4, the blowout mechanism may comprise a pair of guide members 77 and 78 illustratively in the form of V-shaped angle bars affixed in any suitable manner (not shown) so as to be parallel to each other and longitudinally spaced along the conveyor F, each of the legs 79, 81 of the guide members having a stop 82 at the upper end thereof. Desirably the angles 83 of the guide members are positioned slightly below and longitudinally aligned with the troughs 89 of the skew rollers 61 so that clearance is afforded for the metal tubes as they are advanced by the skew roller conveyor F over the angles 83 of said guide members.

Vertically aligned with the angles of the guide members and positioned thereabove between the latter is a horizontal rod 84 rotatably mounted near each end in fixed bearings 85. Securely affixed to rod 84 and extending at right angles thereto are parallel fingers 86 and 87 each of such length that when in vertical position they will extend below the skew roller conveyor F and guide members 77, 78.

Actuating means 88 are desirably associated with said rod to rotate the latter, to move the fingers thereon from the position shown in full

lines in Fig. 4 to the position shown in dot and dash lines. Such means 88 may illustratively comprise a solenoid connected by suitable linkage 89 to rod 84 and controlled by a switch 90 affixed to an arm 91 pivotally mounted at its free end as at 92 so as normally to hang vertically at the end of the blow-out mechanism with the trip member 93 of the switch in the path of movement of the tubes as they are advanced by the skew roller conveyor F.

During the operation of the machine with a tube 24¹⁰ in blow-out position as shown in Figs. 3 and 4, as the metal tube 24⁸ is advanced by the skew roller conveyor system F, the forward end of the tube 24⁸ will abut against trip member 93 to close switch 90. Actuating member 88 through suitable connections (not shown) will thereby be energized to rotate rod 84 through linkage 89 and move the fingers 86, 87 in a clockwise direction from the position shown in full lines in Fig. 4 to the position shown in dot and dash lines. This movement will release tube 24¹⁰ which will move down legs 81 of the guide members until it again rests on the skew roller conveyor system F and pick-up tube 24⁸ which is restrained against forward movement by reason of its abutment against trip member 93, and move the tube 24⁸ up legs 79 of guides 77 and 78 until the tube 24⁸ abuts against stops 82 as shown in dot and dash lines in Fig. 4 and closes switch 94 associated therewith and with guide 77. At the same time the successive tube 24⁹ is being advanced by the skew roller F toward trip member 93.

The closing of switch 94 energizes actuating means 95 which may be affixed for example, to the adjacent end 99 of the roughening unit 71 and which may comprise a solenoid having a plunger 101 associated therewith. The plunger 101 desirably mounts a horizontal cross piece 102 at its outer end which carries at each end thereof respectively the ends of parallel horizontal pipes 103 and 104. Each of said ends extends through and is rigidly affixed to said cross piece and has a funnel-shaped member 105 affixed thereon. Members 105 are so positioned as to be coaxial with the tubes 24 when the latter are positioned against the longitudinally aligned stops 82 at the upper ends of the legs 79 or 81.

The pipes 103 and 104 are slidably mounted in 50 the end wall 99 of the roughening unit 71 with the inner ends of the pipes extending into the casing of such machine. A switch 106 is associated with cross arm 102, having a trip member 107 in the path of movement of plunger 101 of solenoid 98, which trip member when pressed by said plunger will energize solenoid 98 to retract plunger 101 thereof.

Longitudinally aligned with funnels 105 at the other end of the blow-out mechanism are a pair of parallel reciprocable air nozzles 108 and 109 respectively which are to the rear of trip member 93 of pivoted switch 90. The nozzles 108 and 109 control air valves 110 and 111 respectively, which valves are connected to a supply of compressed air desirably dehydrated (not shown), by pipes 112 and 113. The nozzles which have a substantially flat face desirably with a resilient surface are so designed that when pressed they will open the associated valve to permit a jet of air to blow therethrough, a spring 114 being associated with each of said nozzles to retain them in valve closing position.

Energization of solenoid 98 will move plunger 101 thereof forward, carrying with it horizontal cross arm 102 affixed thereon and pipes 103, 104

and thereby advancing the tube 24⁸, the end of which will be lodged in funnel 105, until the other end of said tube abuts against and advances air nozzle 108. This will cause air valve 110 to open to blow a jet of air through the tube 24⁸, funnel 105 and pipe 103, to eject any particles in the bore of the tube into housing 74 of the roughening machine. As plunger 101 reaches the forward end of its stroke it will abut against the trip member 107 of switch 106 which will close to again energize solenoid 98 which will now retract the plunger 101 to move funnel 105 away from the end of tube 24⁸.

At this time tube 24⁹ will have been advanced by the skew roller conveyor F so that its end abuts against trip member 93 to again close switch 90 thereby energizing actuating member 88 which will rotate rod 84 in a counterclockwise direction as shown in Fig. 4 to move fingers 86, 87 back to their original position shown in full lines. This movement will release tube 24⁸ which will move down legs 79 of the guide members until it again rests on the skew roller conveyor system F and pick-up tube 24⁹ to move it up legs 81 until it abuts against stops 82 at the upper ends of such legs to close switch 94 to repeat the blow-out operation previously described.

By reason of the fact that the trip finger 93 is in front of the nozzles 108, 109 as the tubes 24 move down the legs they will abut against the pivoted arm 91 to cam the latter to the side so that the tubes 24 will come to rest on skew roller conveyor F which will again simultaneously rotate and advance the tubes 24 for the next operation.

Metal spraying station "D"

After the metal tubes are blown out as heretofore described, they are successively fed through the metal spraying station D which, as diagrammatically shown in Fig. 1, may comprise a chamber 128 having a plurality of conventional metal spray pistols 129 which though they may be of any suitable type, illustratively may be of the type known in the art as the "Schori" pistol. The pistols 129 are positioned so as to spray a non-ferrous metal coating such as zinc, aluminum, cadmium or the like on the tubes as they are successively advanced thereby, the tubes herein being described by way of illustration as being coated with zinc.

In order that the metal spray be equally distributed in a uniform layer over the entire outer surface of the tubes and that no area of the tube is exposed to the heated metal spray for any excessive length of time, it is desirable that the tubes be simultaneously advanced and rotated at uniform high speed as they are moved past the spray pistols.

Since the skew roller conveyor F effects but an impositive feed, a positive feed mechanism G is required for the spraying operation to assure advance and rotation of the tube at a controllable uniform high rate of speed to prevent the application of excessive heat to any portion of the tube or the application of a non-uniform coating thereon.

The positive feed mechanism G which is positioned between the output of the blow-out station C and the input to the metal spraying station D is more fully shown in Figs. 5 and 6 and comprises a housing 131 which may include a pair of parallel spaced end plates 132 and 133, illustratively circular as shown, between which are positioned a pair of parallel, spaced side plates 134 and 135 illustratively rectangular as

shown, extending at right angles to said end plates and rigid therewith.

End plates 132 and 133 have axial hubs 136 and 137 respectively in which are rigidly affixed hollow shafts 138 and 139 respectively, rotatively mounted in bearings 141 and 142 respectively, in turn rigidly supported in any suitable manner (not shown).

The bores of shafts 138 and 139 are of slightly larger diameter than, longitudinally aligned and coaxial with, the metal tubes 24 carried by the conveyor F, so that the tubes may be moved by such conveyor F into the flared mouth 146 of hollow shaft 138. The end 147 of shaft 138 which extends slightly beyond hub 136, is slightly spaced from the adjacent peripheries 148 and 149 of a pair of gripping rollers 151 and 152 which are rotatively mounted respectively, as shown, on transversely aligned shafts 153 and 154 affixed at each of their ends in the side plates 134 and 135 so as to retain said rollers in the same plane with their axes at right angles to the path of movement of such tubes on conveyor F.

25 The peripheries 148 and 149 of rollers 151 and 152 each desirably has a concave groove 150 therein in each of which a ring of resilient compressible material 155, such as rubber, may be affixed.

30 The concave grooves 150 are spaced by a distance slightly greater than the outer diameter of metal tubes 24 and the resilient rings 155 are spaced by a distance slightly less than such outer diameter so that as the tube is pushed through 35 shaft 138 by conveyor F it will securely be gripped by the resilient rings.

35 Means are desirably provided to rotate rollers 151 and 152 so that the tubes gripped therebetween will enter the flared mouth 157 of hollow 40 shaft 139 and be advanced therethrough.

To this end each of the rollers 151 and 152 has a bevel gear 158 and 159 associated therewith respectively and rigidly affixed thereto. The peripheries of such gears are engaged by a corresponding bevel gear 161 and 162 rigidly affixed on the ends of horizontal shafts 163 and 164 respectively, journaled in and extending through associated bearing openings 165 and 166 in end wall 133.

45 The outer ends of the respective shafts 163, 164 each has a spur gear 167 and 168 affixed thereon which spur gears mesh with a driving gear 171 rotatively mounted on hollow shaft 139, said driving gear 171 desirably having a sprocket wheel 172 rigid therewith operatively connected 50 by means of a sprocket chain 173 to a sprocket wheel 174 upon drive shaft 175.

55 Thus, upon rotation of the driving gear 171 by the transmission from the drive shaft, spur gears 167 and 168 will be rotated in opposite direction to drive shafts 163 and 164 and through bevel gears 161 and 162 to drive bevel gears 158 and 159 and rollers 151 and 152 thereon in opposite direction, thereby to advance the tube 24.

60 As driving gear 171 and sprocket wheel 172 are rotatively mounted on shaft 139 their rotation will not rotate the shaft and hence the metal tube will only be advanced and not rotated. To rotate the tubes, a sprocket wheel 176 is rigidly affixed to shaft 139 and operatively connected by a sprocket chain 177 to a sprocket wheel 178 affixed on drive shaft 175.

65 Thus, upon rotation of said drive shaft 175, as hollow shaft 139 is rigidly affixed to the housing 131, the latter will be rotated to rotate the

11

tube 24, while the rotation of the rollers 151 and 152 will advance the metal tube.

By changing the size of the sprocket wheels it is a relatively simple matter to adjust the speed of rotation and advance of the metal tube.

Although with the installation herein described a non-ferrous coating of one metal is applied to the tubes, it is of course to be understood that two or more coats of the same or diverse metals could be applied to the tubes or if desired a paint coating could be applied on a metal coating.

Burnishing station "I"

Where it is desired to smooth slightly the roughened surface of the metal tubes 24 after they emerge from the spraying station, a burnishing station I may be provided. This station may comprise a pair of circular wire brushes 181 and 182 having their peripheries almost in engagement and mounted in any suitable manner so as to rotate desirably in a clockwise and counter-clockwise direction respectively.

In order that the metal tubes may be positively gripped as they are advanced between the brushes 181 and 182 to be acted upon thereby, a positive feed mechanism G¹ is desirably provided at the input of the burnishing station I and desirably, though not necessarily, a positive feed mechanism G² is provided at the output of the burnishing station.

As the construction and operation of said mechanisms G¹ and G² is identical to that of positive feed mechanism G they need not be further described.

Painting station "E"

The metal sprayed, and if desired, burnished tubes are then internally coated with suitable quick drying, flexible paint, lacquer or varnish. Although the tubes may be moved in lengthwise sequence through the painting station, for convenience they are moved not in lengthwise sequence, but at right angles to their lengths. The tubes to that end may be moved in such direction as they emerge from station D or I as the case may be, that is out of the plane of the sheet as shown in Fig. 1. In a desirable installation that does not require an L-shaped floor lay-out as that just mentioned, the specific arrangement shown in Fig. 1 may be employed.

As the metal tubes are advanced by positive feed mechanism G² they may be discharged upon a pivoted transfer arm 183, having means associated therewith (not shown) to pivot the arm in a clockwise direction as shown in Fig. 1 through an arc of approximately 90 degrees to carry the outer end of the tube thereon up an inclined track 184 to the painting station E and after depositing such tube, pivoting back to its original position to receive the next tube.

This station may include a painting gun 185 registering with the upper end 186 of the inclined tube 24 and pushing means which illustratively comprises a solenoid 187 registering with the lower end 188 of the tube.

Although the painting gun 185 may be of any suitable type, as shown in Fig. 7 it desirably comprises a tubular housing 189 having a plug 190 rigidly affixed therein with a bore 191 therethrough of slightly larger diameter than the outer diameter of the tube 24.

Slidably mounted in the housing 189 is a disc shaped trigger member 192 having a bore 193 therethrough of smaller diameter than the outer diameter of the tube 24 and coaxial with the bore

12

of plug 190, said bore 193 being outwardly flared at 194, 195. Trigger member 192 is normally retained against the end face 196 of plug 192 by a coil spring 197 compressed between the end wall 5 198 of the housing 189 and the inner face 199 of the trigger member 192, the latter having a pin 201 rigidly affixed thereto at one end and extending longitudinally of housing 189 through an opening 202 in end wall 198.

Housing 189 mounts a paint nozzle 203 which comprises a tubular casing 204 rigidly affixed in end wall 198 coaxial with bores 191 and 193. The nose end 206 of casing 204 has a valve member 207 seated thereon and an actuating rod 15 208 affixed at one end to the valve member 207, is slidably mounted in a suitable bearing 211 in casing 204 and protrudes through the end wall 212 thereof.

By means of a coil spring 213 compressed between the inner face 214 of bearing 211 and a collar 215 affixed on rod 208, the latter is normally held in retracted position, thereby retaining the valve member 207 on its seat 206 to close the valve.

25 The rod may be actuated by suitable means such as a solenoid 216 affixed to the end 217 thereof, which solenoid is controlled by a switch 218 having a finger 219 in the path of movement of pin 201.

30 To supply paint to the paint nozzle, a pressure chamber 221 is connected to the casing 204 by inlet pipe 222 and pipe 223 is connected to a source of paint (not shown).

In the operation of the painting station, as 35 the metal tube 24 is aligned with the painting head 185 and the solenoid 187 by the transfer arm 183, the solenoid 187 will momentarily be actuated to push the tube upwardly so that the upper end 186 thereof enters the bore of plug 40 190 and forces trigger member 192 and pin 201 forward against the resistance of spring 197. When pin 201 abuts against finger 219 of switch 218 the latter will close to actuate solenoid 216 thereby advancing rod 208 to open the valve 207 and a fixed quantity of paint maintained under pressure in chamber 221 will be ejected into the tube 24.

As solenoid 187 is no longer energized at this time, coil spring 197 will quickly return trigger 50 member 192 to eject tube 24 from the bore 191 of plug 190 at the same time releasing switch 218 so that the valve member 207 will be reseated by spring 213.

The tube 24 will thereupon be picked up by 55 conveyor system H so that the paint ejected therein may be distributed on the inner surface thereof in the manner hereinafter described.

The conveyor system H comprises an inclined substantially rectangular bed 231 having up-standing walls 232, 233 on each side thereof upon which the tubes 24 may rest. An endless conveyor belt 235 is desirably associated with each of said walls respectively, said belts having a plurality of spaced fingers 236 extending at right angles thereto with transversely aligned pairs of fingers on said belts engaging successive tubes and moving them along said walls 232, 233.

70 Preferably the upper edges 241 of the walls are roughened so that as the tubes are advanced thereon by the fingers 236 the tubes will rotate. This rotation in conjunction with the inclination of the tube on bed 231 causing the paint ejected in the tube to be equally distributed along the entire inner surface thereof.

75 The residual heat remaining in the tubes from

the spraying operation will be sufficient to hasten the drying of the paint and hence increase the efficiency and rate of output of the installation. If desired, in order further to hasten the drying of the paint in the tubes, hot air blowers 242 and suction devices 243 may be positioned along each side of the bed, aligned with the bores of the tubes.

Thus, in but a few minutes after the paint is injected into the tubes, it will be equally distributed thereon and dried so that the completed tubes may be discharged from the conveyor H ready for inspection, labeling, packing and distribution.

It is also within the scope of the invention to interpose a blow-out unit between the metal spraying unit and the painting station. If so located, the metal tubes on the conveyor may have their ends in close juxtaposition as they are passed through the spraying unit as the lengthwise spacing of the tubes which is required for the action of the blow-out unit would not be needed. Hence the number of tubes that could be passed through the spraying unit in a given period would be increased with a consequent increase in the output of the installation. However, with the blow-out unit away from the roughening unit, the particles discharged from the tubes would not be blown back into the roughening unit.

Although the illustrative embodiment of the invention herein described is designed to act upon one tube at a time, it is within the scope of the invention to act upon pairs of tubes as they are advanced through the installation.

To this end two tubes could be simultaneously discharged onto the conveyor F from the degreasing unit in which two or more tubes may be carried by each of the pairs of associated fingers of the conveyor 15 and 16 or, as shown and described herein, a single tube may be carried by each of the pairs of associated fingers. The conveyor F may thereupon carry the pair of tubes through the roughening station to be acted upon thereby, to the blow-out station which could be designed according to the principles set forth herein, to lift the two tubes simultaneously to present them to an air nozzle of sufficient width to accommodate the ends of the two tubes in order to discharge a jet of air through both tubes concurrently, whereupon such tubes are transferred to positive feed mechanisms to be passed through metal spraying units and subsequently deposited upon a transfer arm and conveyed thereby to the painting unit for injection of a quantity of paint into the bores of the tubes.

With the installation herein described, metal tubes may be degreased, roughened and cleaned, particles removed from the bore thereof, a metal coating of uniform thickness sprayed on the exterior of the tubes and painted on the interior thereof and dried all in a speedy, continuous operation without manual handling. As the heated metal particles from the spray guns are sprayed on the tube while it is being rapidly rotated and advanced, the particles will congeal rapidly and although the tube will become sufficiently heated to aid in the drying of the paint subsequently injected therein, no portion of the tube will be exposed to high temperature for any considerable period of time.

The resultant product thus has a roughened coating of pure non-ferrous metal, illustratively of zinc formed from the discrete particles sprayed thereon which congeal to completely cover the

outer surface thereof with a mat finish and forming substantially an integral part of the tube and a coating of flexible paint on the inner surface thereof which coatings are ductile and pliable and will hence enable the tube to be bent without cracking of such coatings and especially of the outer coating which might cause rusting of the metal tube therebeneath.

By congealing is meant the conversion to the firm or relatively rigid non-flowable condition of the metal particles which emerge from the spray guns in flowable or plastic state.

Although the installation above described has been shown as applied to relatively thin walled metal tubing, it is of course to be understood that it could just as readily be applied to metal tubing having regular pipe wall thickness.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. An installation of the character described for coating metal tubes, comprising a metal spraying unit having a fixed spray nozzle, means to grip and simultaneously and positively to rotate such tubes and advance the latter lengthwise through said metal spraying unit past said fixed spray nozzle to be acted upon thereby, whereby the entire outer surface of such tubes may be uniformly coated without any portion thereof being subjected to the action of said spraying unit for any excessive period of time, the means for gripping such tube and simultaneously rotating and advancing the same comprising a housing, means rotatably mounting said housing, a pair of rollers rotatably mounted in said housing lying in the same plane with their axes parallel to each other, said rollers having their peripheries spaced from each other and having gripping means thereon, means to guide a tube into said housing between said rollers to be gripped thereby, drive means to rotate said rollers to advance the tube therebetween, means to guide such tube out of said housing from said rollers and drive means to rotate said housing.

2. An installation of the character described for coating metal tubes, comprising a metal spraying unit having a fixed spray nozzle, means to grip and simultaneously and positively to rotate such tubes and advance the latter lengthwise through said metal spraying unit past said fixed spray nozzle to be acted upon thereby, whereby the entire outer surface of such tubes may be uniformly coated without any portion thereof being subjected to the action of said spraying unit for any excessive period of time, the means for gripping such tube and simultaneously rotating and advancing the same comprising a housing having a pair of end plates, a pair of rollers rotatably mounted in said housing lying in the same plane with their axes parallel to each other, said rollers having their peripheries spaced from each other and having gripping means thereon, a pair of hollow axial shafts affixed respectively in each of said end plates and extending into said housing, means rotatably mounting said hollow shafts, the inner ends of each of said hollow shafts being slightly spaced from the peripheries of said

15

rollers and longitudinally aligned with a space therebetween, whereby one of said hollow shafts may guide such tube into said housing between said rollers and the other of said hollow shafts may guide such tube from said rollers out of said housing, drive means operatively connected to said rollers to rotate the latter to advance the tubes therebetween and drive means to rotate said hollow shafts and said housing to which they are affixed.
